UNITED STATES PATENT OFFICE.

NATHAN GEWANDTER, OF GARDNER, MASSACHUSETTS.

CHILD'S GARMENT.

1,199,689.

Specification of Letters Patent. Patented Sept. 26, 1916.

Application filed February 25, 1916. Serial No. 80,475.

To all whom it may concern:

Be it known that I, NATHAN GEWANDTER, a citizen of the United States, residing at Gardner, in the county of Worcester and State of Massachusetts, have invented certain new and useful Improvements in Children's Garments, of which the following is a specification.

My invention is an improvement in under garments for children's use, comprising a waist portion and drawers made in one piece with shoulder bands for the waist portion and an opening at the back closed by buttons, with means for holding stocking supporters detachably, and to prevent chafing of the body by the metallic connections.

In the accompanying drawing, Figure 1 shows a general view of the garment, the opening at the back being shown in dotted lines, and Fig. 2 is an inside view of the front of the garment showing the hose supporters and their connection with the waist band.

The waist of the garment is shown at *a*, having shoulder straps *b*, which are made in one piece with the back of the waist and buttoned to the front. The back of the waist *c*, is secured to the drawers by a buttoned band *d* forming a part of the drawers, while the drawers and waist are connected together at the front by a waist band *e*.

As shown in Fig. 2 I form a flap *f* on the inside, depending from the top of the waist band and preferably of doubled material, this flap having parallel openings in the nature of buttonholes *g*, near each outer

edge, and these are adapted to receive safety pins *h*, for ready detachment, these pins being secured to the upper end of elastics *i*, which are provided at the lower ends with ordinary hose supporters *k*. A second flap *l*, also secured to the upper edge of the waist band on the inner side of the garment is adapted to fold over the flap *f*, and cover the safety pins and protect the body of the wearer against abrasion or contact with said safety pins or other metallic holders. This forms a very simple but effective construction and is so strong as to make it almost impossible for the safety pins to pull out under the ordinary wear and tear that such garments are subjected to, while at the same time the safety pins may be readily detached for laundry purposes.

What I claim is:

A child's garment comprising a combination waist and drawers, with an attachment for stocking supporters, consisting of two superimposed flaps secured to the garment at the waist line, each of the flaps extending across substantially the entire front of the waist band, the inner flap having a plurality of openings spaced apart and adapted to receive safety pins from which the stocking supporters depend, and the outer flap covering the inner flap, substantially as described.

In testimony whereof I affix my signature in the presence of two witnesses.

NATHAN GEWANDTER.

Witnesses:

EDWARD K. CAMPBELL,
HERBERT W. BLAKE.
